This invention relates to a new class of photographic developing substance and to the use thereof in the development of silver halide photographic emulsion layers.

In specification No. 542,502 there is described a process for the development of reducible silver salt images in photographic materials which comprises treating the materials with an aqueous solution containing a 3-pyrazolidone of the general Formula I:

where R_1 , R_2 and R_3 are the same or different and are hydrogen atoms or hydrocarbon groups.

Of the foregoing compounds, the compound 1-phenyl-3-pyrazolidone has received widespread commercial use, for which purpose it is customarily employed in association with another photographic developing substance with which it exhibits a superadditive effect. Thus it may be used in association with hydroquinone, hydroxyphenyl glycine, gentisic acid, ascorbic acid, reductone and other substances.

Subsequently it was shown that similar, though not necessarily identical, developing characteristics were possessed by corresponding compounds in which the one or both of the hydrogen atoms shown in the 4 and 5 positions of the compounds of the foregoing formula were replaced by substituent groups such as hydrocarbon residues.

A difficulty which has been experienced with the compound 1-phenyl-3-pyrazolidone lies in its limited solubility in alkaline media.

It has now been found that 3-pyrazolidone derivatives as defined below are extremely useful developing agents at high pH values and have a substantially greater solubility.

According to a first feature of the present invention there are provided 3-pyrazolidone derivatives of the general Formula II:

wherein R_1 is a heterocyclic substituent and R_2 is an aryl, substituted aryl or heterocyclic group.

In the foregoing formula R_1 may be, for example, furyl, thieryl, pyranyl, indolyl, pyridyl, thiazolyl, piperidyl, morpholinyl, pyrrolidinyl or benzimidazolyl. R_2 may be, for example, a phenyl group or an alkyl, alkoxy, halogen- or other substituted phenyl group, or any of the heterocycles referred to above.

These compounds are not effective photographic developing agents for silver halide emulsions at pH values below about 9.5. At pH values above that level they show a very strong superadditive effect with such auxiliary developing substances as hydroquinone, and they have the especial merit of having a high solubility in highly alkaline solutions.

Processes for the production of the 3-pyrazolidone types of developer compound are described, for example, in specifications Nos. 542,502, 703,669 and 728,368. Of the various known methods, those of specifications Nos. 703,669 and 728,368 can most readily be adapted to the production of compounds according to the present invention, and according to further features of the present invention, therefore, compounds of general Formula II are prepared by:

10 (a) Reacting a hydrazine of the general Formula III:

$$R_2\text{NH.NH}_2 \quad (\text{III})$$

with an ester of the general Formula IV:

$$R_1\text{—CH=CH—COOR}_3 \quad (\text{IV})$$

15 where R_3 is a hydrocarbon group and the other symbols have the meanings hereinbefore assigned.

(b) Reacting a hydrazine of the general Formula III with an amide of the general Formula V:

$$R_1\text{—CH=CH—CONHR}_3 \quad (\text{V})$$

(c) Reacting a hydrazine of the general Formula III with a compound of the general Formula VI:

$$R_1\text{—CH=CHCN} \quad (\text{VI})$$

20 and subjecting the resulting 3-imino pyrazolidone to hydrolysis.

(d) For the production of compounds of general Formula II where R_1 is a benzimidazole residue reacting a compound of the general Formula VII:

25 with an orthophenylene diamine.

The new developing substances of the present invention may be used in the same manner as 1-phenyl-3-pyrazolidone, but at pH values above 9.5, in association with hydroquinone, hydroxyphenyl glycine, or any other known developing agent with which the new compounds exert a superadditive effect.

The following examples will serve to illustrate the invention:

EXAMPLE 1

1-phenyl-5-2'-pyridylpyrazolidin-3-one

A solution of sodium (6.0 g.) in ethanol (100 ml.) was treated successively with benzene (100 ml.), phenylhydrazine (20 ml.) and ethyl 3-2'-pyridylacrylate (35 g.) and the mixture was refluxed for 16 hours. The residue remaining after distillation of the solvents was refluxed for 3 hours with concentrated hydrochloric acid (100 ml.). The resulting solution was treated with crystalline sodium acetate (140 g.) and cooled. The oil which separated initially solidified rapidly, and the product was crystallised from a mixture of ethanol and ethyl acetate to yield the pyrazolidin-3-one as colourless needles, M. Pt. 191–2°.

EXAMPLE 2

1-phenyl-5-3'-pyridylpyrazolidin-3-one

This was prepared by the method of Example 1, but using ethyl 3-3'-pyridylacrylate. The pyrazolidin-3-one formed colourless plates, M. Pt. 127–128°, by crystallisation from ethyl acetate.

EXAMPLE 3

1-phenyl-5-4'-pyridylpyrazolidin-3-one

The method of Example 1 was used with ethyl 3-4'-pyridylacrylate. The pyrazolidin-3-one formed colour-
